UNITED STATES PATENT OFFICE

2,202,262

BEER COOLING AND DRAWING SYSTEM

John Panagopoulos, Youngstown, Ohio, assignor
to Novadel-Agene Corporation, a corporation
of Delaware

Application July 16, 1937, Serial No. 153,903

5 Claims. (Cl. 225—1)

The present invention relates to the art of beer cooling and dispensing and involves a special application of the invention broadly disclosed and claimed in Patent No. 2,051,013, issued August 11, 1936, to Herman E. Schulse.

Among the objects of the invention are to provide an installation of the above type in which the brew from the keg is dispensed at a remote spigot either on the floor above that of the keg or on the same floor, but at a bar remote from the keg, the brew being cooled and maintained cool not only within the keg but also through its course of flow to the remote faucet.

Another object is to provide an installation of the above type adaptable both to small and to large beer dispensing establishments, permitting of great flexibility in the positioning of the kegs being cooled and on tap, for supplying more than one bar either from kegs on the tavern floor or in the basement or distributed, if desired, some on the tavern floor and others in the basement.

The device shown in this application is an improvement over a portion of the device shown in my co-pending application filed March 25, 1937, Serial Number 132,977, upon which Patent No. 2,194,319 was granted March 19, 1940.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein—

Figure 1 is a side elevation of the device partly in cross section.

Figure 2 is an enlarged detail view of the terminal chamber member with only one beer outlet shown.

By referring to the drawing it will be seen that there is provided a bar 1. A cooling tank 2 is positioned within the bar 1 and houses a refrigerating coil C and has a vertical cooling chamber 3 positioned below it. This vertical cooling chamber 3 comprises an upper and a lower tube 4 having a smaller tube 5 positioned within it, the space between the tubes 4 and 5 being closed at the top by a closure 6. The tube 4 has a closure 7 at the bottom. The upper tube 4 and the lower tube 4 are connected by a flexible tube 8 held in position by clamps 10. A pipe 8 is tapped into the side of the upper tube 4 and is formed so that its upper end is positioned near the top of the cooling tank 2 and is provided with

a plurality of openings 11. A lower end of the tube 5 extends below the closure 7 and has attached thereto a terminal chamber member 12. The terminal chamber member is provided with a detachable bottom portion 13.

By referring to Figure 2 it will be seen that this detachable bottom portion 13 is held in position by means of bolts 14 and is provided with a gasket 15 in order to efficiently seal the bottom portion 13 to the terminal chamber member 12. It will be seen that the extreme upper portion 16 is provided with internal threads 17 in order that the terminal chamber member may be easily attached and removed from the lower end of the tube 5.

By referring to the drawing it will be seen that couplers 18 are provided on the terminal chamber member. These couplers 18 are provided in order to join flexible beer outlet tubes 19, one of which is shown, to the lower sections of beer outlet tubes 20 which extend upwardly through the tube 5 and through the cooling tank 2 and lead to outlet spigots 21. By referring to Figure 2 it will be seen that one of these couplers 18 is shown in detail in cross section.

It will be seen that there is also provided a second bar 22 having located therein a cooling tank 23 with a refrigerating coil C therein. Adjacent to this cooling tank 23 there is provided a manifold including a circulating member 24 comprising an outer tube 25 and a smaller inner tube 26. One end of the smaller tube 26 extends into the cooling tank 23 and has a plurality of openings 27 therein. The outer tube 25 is provided with a plurality of taps 28 leading into a chamber 29 formed between the interior of the tube 25 and the exterior of the tube 26. The inner tube has a plurality of branch pipes connected thereto with terminals 33 exposed at the outside of tube 25.

A barrel 31 with cooling conduit 32 therein, only the terminals 30' and 32' of which are shown, is connected through said terminals respectively with one of the taps 28 and 33 by means of tubes 30 and 32 respectively. Other kegs may similarly be connected to the manifold across other pairs of terminals designated by numerals 28 and 33. It will be seen that there is a beer outlet tube 34 from the barrel 31 which connects to one of the taps 35 located on the tube 25. These taps are joined to beer outlet tubes 36 carried within the chamber 29 and extending through the cooling tank 23 to outlet spigots 37.

It will be seen that adjacent and attached to the tube 5 at a point 38 there is a manifold 39 comprising an outer tube 40 and a smaller tube 41, thereby providing a chamber 42 for the purpose of carrying a circulating cooling agent. It will be seen that the outer tube 40 is provided with a plurality of taps 43 leading to the chamber 42. One of these taps 43 is attached to a 60

tube 44 leading to a barrel cooling system positioned within a barrel 45. A tube 46 leads from the cooling system of the barrel 45 and connects to one of a plurality of taps 47 which lead to 5 the interior of the inner tube 41.

It will be seen that there is provided a tube 48, one end of which is attached and leads into the cooling tank 23 at a point 49. The other end of the tube 48 is attached to the outer end 10 50 of the inner tube 41. The inner end of the tube 41 leads to the interior chamber of the tube 5. There is also provided a tube 51, one end of which is attached and leads into the outer tube 25 at a point 52, while the other end is attached 15 and leads into the lower tube 4 at a point 53. It will also be seen that the tube 51 and the outer tube 40 are connected at points 54 and 20 55 by means of a tube 56. Positioned on this tube 56 is a circulating pump 57 for the purpose of circulating the cooling agent throughout the device.

What I claim is:

1. In a device of the class described, a cooling tank positioned underneath a bar, an upper and lower outer tube extending downwardly from the bottom of said tank, a tube joining said 25 upper and lower tubes, an inner tube positioned within said tubes and extending beyond the lower end thereof thereby forming a chamber between the tubes, closures formed at the upper and lower ends of said chamber, a tube leading from said chamber into said cooling tank, a terminal chamber member attached at the lower end of said inner tube, a bottom member formed 30 on said terminal chamber member, a plurality of beer outlet pipes extending upwardly through said terminal chamber and the inner tube and through said cooling tank to outlet spigots, taps attached to lower ends of said beer outlet pipes 35 for the purpose of attaching beer outlet tubes leading to barrels, a manifold attached to a side of said inner tube comprising an outer and inner tube spaced apart thereby forming a chamber closed at both ends, said inner tubes communicating with each other, a plurality of taps leading to said inner tube of said manifold for 40 providing means for attachment to the inner circulating systems of barrels, a pump and connecting tubes leading to the said chambers, a second cooling tank, said inner tube of the manifold having circulating communication therewith, a second manifold, one of said connecting tubes 45 having circulating communication with the latter for the purpose of circulating a cooling agent.
2. In a device of the class described, a cooling tank positioned underneath a bar, an upper and lower outer tube extending downwardly from the bottom of said tank, a flexible tube joining said 50 upper and lower tubes, an inner tube positioned within said tubes and extending beyond the lower end thereof thereby forming a chamber between the tubes, closures formed at the upper and lower ends of said chamber, a tube leading from said chamber into said cooling tank and having a plurality of openings therein, a detachable terminal chamber member attached at the lower end of said inner tube, a detachable 55 bottom member formed on said chamber member, a plurality of beer outlet pipes extending upwardly through said terminal chamber and the inner tube and through said cooling tank to out-

let spigots, taps attached to lower ends of said beer outlet pipes for the purpose of attaching beer outlet tubes leading to barrels, a manifold attached to a side of said inner tube comprising an outer and inner tube spaced apart thereby 5 forming a chamber closed at both ends, said inner tubes communicating with each other, a plurality of taps on said outer tube leading to said chamber in the said manifold and a plurality of taps leading to said inner tube of said manifold for 10 providing means for attachment to the inner circulating systems of barrels, a pump and connecting tubes leading to the said chambers, a second cooling tank, said inner tube of the manifold having circulating communication therewith, a second manifold, one of said connecting tubes having circulating communication with the latter for the purpose of circulating a cooling agent.

3. In a brew cooling and dispensing installation, a cooling tank having cooling liquid therein, a manifold exteriorly of and connected to said tank and comprising an outer tube attached to the tank and an inner tube delivering into the tank and a plurality of pairs of taps exposed at 25 the exterior of the manifold, each pair in communication with the respective tubes of the manifold, a plurality of kegs incorporating cooling conduits and releasably connected to respective pairs of taps, a pump drawing cooling fluid from 30 the tank and delivering into the outer tube of the manifold thence through the kegs in parallel, the inner tube of the manifold and back to the tank in a continuous cycle of operation.

4. In a beer cooling and dispensing installation, a bar having a cooling tank therein, beer faucets at the front of said tank, a manifold in communication with said tank, said manifold including an outer tube and an inner tube, a pump delivering cooling liquid from said tank to said 40 outer tube of the manifold, said inner tube of the manifold delivering liquid back to the tank, the respective tubes of said manifold having taps exposed at the exterior of the manifold to afford the sole external connection between said tubes, 45 beer kegs incorporating cooling conduits connected to said taps for such external connection and beer feed lines from those of the respective kegs on tap, extending through the outer tube of the manifold and through the tank to the 50 respective faucets.

5. In a brew cooling and dispensing installation, a cooling tank positioned underneath a bar, a vertical cooling chamber communicating with said tank, a horizontal manifold comprising cooling liquid delivery and return tubes, one of said tubes being connected to said vertical cooling chamber, a plurality of pairs of taps exposed at the exterior of the manifold, each pair in communication with the respective tubes of the 60 manifold, a plurality of kegs incorporating cooling conduits and releasably connected to respective pairs of taps, a pump drawing cooling fluid from the tank and delivering into one of the tubes of the manifold thence through the kegs 65 in parallel to the other tube of the manifold and means forming a passageway from the pump back to the tank in a continuous cycle of operation and beer conduits from the respective kegs extending upward through the vertical cooling 70 chamber and through the cooling tank.

JOHN PANAGOPoulos.
